UNITED STATES PATENT OFFICE.

GUY H. CHRISTY, OF SANTA CRUZ, CALIFORNIA, ASSIGNOR OF TWO-FIFTHS TO OLIVER BOYEA, OF SANTA CRUZ, CALIFORNIA.

MAIL-BAG-CAST-OFF DEVICE.

1,129,273.

Specification of Letters Patent. Patented Feb. 23, 1915.

Application filed March 16, 1914. Serial No. 324,897.

To all whom it may concern:

Be it known that I, GUY H. CHRISTY, a citizen of the United States, residing at Santa Cruz, in the county of Santa Cruz and State of California, have invented new and useful Improvements in Mail-Bag-Cast-Off Devices, of which the following is a specification.

This invention relates to mail delivering apparatus, and particularly to an apparatus for throwing or casting off mail bags from traveling railway cars.

It is an object of the present invention to provide a substantial and easily operated and reliably acting device for delivering or casting off mail bags from railway trains while the cars are in motion.

The invention consists of the parts and the construction and combination of parts as hereinafter more fully described and claimed, having reference to the accompanying drawings, in which—

Figure 1 is a side elevation of a portion of a railway car, showing the apparatus as adjusted in preparation for the delivery of mail. Fig. 2 is a transverse vertical section through the car, showing the apparatus in side view.

In the drawings, 2 represents a portion of a railway car having a doorway or window 3. There is secured on the side of the car suitable bearing brackets 4, in which is supported a crane 5 turnable about a vertical axis in the bearings 4. The crane 5 is provided at its lower inner end with a pintle 6, through which and the adjacent bearing 4 may be run a locking pin 7, flexibly connected by a cord or other device 8 attached to the body of the crane, and which pin is adapted to lock the crane 5 in desired angular position with relation to the side of the car.

In the present drawings the crane is shown as locked to stand perpendicularly from the side of the car, in which position it is designed to support one or more mail bags, as indicated at 10; these being strapped or suitably attached to a shackle or ring 11 which is adapted to pass between spaced eyes 12, on the bottom of the crane, and through the eyes there is insertible a pin 13 which projects also through the ring or shackle 11 carrying the mail bags, as shown in Fig. 1. The operator adjusts the mail bags to the shackle ring 11, and in turn

inserts this between the eyes 12, when the crane is drawn into a position parallel to the window 3 and the crane is then thrown outwardly into perpendicular position and locked by the locking pin 7.

The pin or bolt 13 is pivotally connected at 14 to the lower end of an arm 15, which in turn is connected at its upper end to a rocker-shaft 16, supported in suitable bearings on the crane 5. The outer end of the rocker-shaft 16 is provided with a lever 17, one arm of which projects downwardly and is connected to a spring 18, connected at its opposite end to a bracket or hanger 19 of the crane, the spring 18 operating normally to draw the pin arm 15 inwardly toward the crane and project the pin 13 through the aligned eyes 12 and thus lock the shackle 11 in suspended position on the crane.

The upper end of the lever 17 is pivotally connected at 20 to a connecting link 21, the opposite end of which is mounted upon a crank 22 of a crank-shaft 23 which is supported, horizontally, in bearings 24 of the crane 5. The outer end of the crank-shaft 23 carries an operating lever 25 which may be turned upwardly, as is shown in the present drawings, to throw the crank 22 upwardly as to the center of the bearings 24 and at the same time thrust the lever 17 so that the pin arm 15 will move the pin 13 into the eyes 12, although the lever 25 may be turned downwardly and throw the crank 22 below the center of the shaft 23 with the similar result of moving the pin 13 into the eyes 12.

When the mail bags have been pinned to the crane by adjustment of the shackle ring 11 between the eyes and upon the pin, and the crank 22 thrown to rock the lever 17, the operating lever 25 will then stand, if thrown upwardly, in the position shown in Figs. 1 and 2. When the station is reached at which it is desired to throw off the mail bags, the arm 25 will be engaged by a stationary striker or abutment member, which is here shown as a roller 26, on a horizontally projecting arm 27 of a post or suitable support 28. As the moving car carries the upwardly projecting operating lever 25 against the striking roller 26, the reaction of the striking roller 26, upon the pivoted lever 25, will throw the latter downward and simultaneously rock the crank-shaft 23 so as to swing

the crank 22 rearwardly and downwardly; the crank operating through the connecting link 21 to draw over the upper end of the releasing lever 17, the lower end of which 5 will move outwardly away from the eyes 12 and withdraw the pin 13 therefrom and from the ring 11, which, being released from the crane, will permit the delivery of the mail bags at the predetermined station.

10 After the operating lever 25 has been tripped by the striking roller 26 and the crank-shaft 23, with its crank, thrown so as to withdraw the pin 13 through the actuating lever 17 and arm 15, the pin 13 will 15 hang freely at the lower end of its arm 15 and the spring 18 will automatically contract and hold the parts against rattling. In the event that the operating arm 25 is thrown to its lowermost position by the operator, it is understood that the striking roller 26 at the station would, of course, be positioned in a lower plane as shown in dotted lines, so as to engage the lever.

Having thus described my invention, what 25 I claim and desire to secure by Letters Patent is—

1. In a mail bag handling apparatus, a crane having a keeper to receive the mail bag shackle, a horizontal pin slidable 30 through the keeper and shackle to support the latter, a rock shaft on the crane, a link on the rock shaft depending therefrom and pivoted to said pin, a lever connected 35 between its ends to the rock shaft, a hanger on the crane, a spring connected to the hanger and the lower end of the lever, a crank shaft connected to the upper end of the lever, and an operating lever connected to the crank shaft.

40 2. In a mail bag handling apparatus, a crane having a keeper to receive the mail bag shackle, a pin slidable through the keeper and shackle, a rock shaft, means connected to the pin and rock shaft for actuating the 45 former from the latter, a crank shaft, means on the rock shaft connected to the crank shaft to enable the latter to actuate the for-

mer; means on the crank shaft to operate same, and means to tension the first named means whereby to normally hold the pin in 50 shackle locking position and to hold said operating means on the crank shaft in operative position.

3. In combination with a crane having a keeper and means coacting with the keeper 55 to hold a mail bag, means to actuate said first named means to release the bag, vertically disposed means, means to connect the vertically disposed means and the actuating means, to operate the actuating means, and 60 means to tension the actuating means whereby to hold the first named means in bag holding position and to also hold the operating means in vertical position.

4. In combination with a crane having a 65 keeper and means coacting with the keeper to hold a mail bag, a rock shaft, means connected to said first named means and to the rock shaft to actuate the first named means, a crank shaft, means to connect the rock 70 shaft to the crank shaft, a vertical element connected to the crank shaft for operating same, and means to tension the rock shaft whereby to both hold the first named means in bag locking position and to hold said ele- 75 ment in vertical position.

5. In combination with a crane having a keeper and means coacting with the keeper to hold a mail bag, a rock shaft, means connected to said rock shaft and to the first 80 named means to actuate the latter, means to actuate the rock shaft, a vertical element connected to the last named means to operate the same, and means to tension the rock shaft whereby to hold the bag holding 85 means in operative position and to hold said element in vertical position.

In testimony whereof I have hereunto set my hand in the presence of two subscribing witnesses.

GUY H. CHRISTY.
